ATTORNEYS

UNITED STATES PATENT OFFICE.

FRANCIS MARION HOBBS, OF HALESBORO, TEXAS.

ALARM.

No. 822,125.

Specification of Letters Patent.

Patented May 29, 1906.

Application filed October 21, 1905. Serial No. 283,782.

To all whom it may concern:

Be it known that I, FRANCIS MARION HOBBS, a citizen of the United States, residing at Halesboro, in the county of Red River 5 and State of Texas, have invented a new and Improved Alarm, of which the following is a specification.

My invention relates to alarms for general use.

10 The object had in view is to provide an alarm for attachment to windows, whereby upon raising the lower sash thereof or lowering of the upper sash a bell forming part of the alarm will be sounded, indicating to inmates of the house that a burglar or other person is attempting to effect entrance thereinto through the window.

While the prime object had in view pertains to alarms for windows, it is to construct 20 a device of this character adapted for use in conjunction with any movable part and indicate the movement by ringing of a bell attachment.

With the above objects in view I have invented the simple, novel, and improved 25 alarm shown by the accompanying drawings, and hereinafter described in detail.

In the drawings, Figure 1 is a view showing sectional portions of the upper and lower 30 sashes of a window with my improved alarm applied thereto, the same being illustrated in side elevation. Fig. 2 is a similar view looking at the other side of the alarm. Fig. 3 is a top plan view of the alarm shown applied. In the view portions only of the 35 sashes are shown. Fig. 4 is a detail sectional view taken transversely through the rubber-tired operating-wheel, the combined ratchet and tappet wheel, and the pivotal lever. Fig. 40 5 is a perspective view of the combined ratchet and tappet wheel, and Fig. 6 is a side elevation of the operating-wheel.

In the preferred form of my improved alarm I employ a base-plate A, having 45 spaced lugs or standards B, providing pivotal support therebetween at C for a suitably-fashioned lever D. The lever is pivoted to the lugs B, leaving a short finger end E and a longer curved end F.

50 On the base-plate A, I secure a suitable spring G, having its free end G' disposed between the lugs B and resting with tension against the under side of the finger end E of the lever D.

55 For adjusting position or limiting movement of the lever D, I arrange thereon a

screw H, disposed through its longer end F, as shown in Figs. 1 and 2. The screw is provided with any suitable operating-head I and arranged with its inner end contacting 60 the spring G, though obviously the screw may be arranged to contact any portion of the base-plate A. With this construction it is apparent that pivotal movement of the longer or curved end F of the lever D may be 65 adjusted as required.

In further carrying out my invention I provide a transverse pin or journal J at the free end of the curved portion F of the lever D and arrange thereon a suitable wheel K, 70 having a rubber or other friction-rim L. The pin J provides support for a wheel M, having tappet-teeth N. It will be noticed that the wheel M is located on the pin J, between the wheel K and the lever D, and that its face or side adjacent to the wheel K has a circular series of ratchet-teeth O. (See Figs. 4 and 5.)

The wheel K is provided with a suitable yielding dog or pawl arranged for engaging 80 the ratchet-teeth O on the tappet-wheel M, and the same may consist of a pin P, arranged in a suitable transverse opening Q.

The pin P is held in the opening Q by a spring R and its inner end held yieldingly in 85 contact with the ratchet-teeth O on the tappet-wheel K by elasticity of the spring, as will be understood.

On the longer or curved end F of the lever D, I suitably support a bell S, adapted to be 90 sounded by a head T (see Fig. 2) at one end of an arm U, pivoted at V to the lever D. The arm U is extended beyond its pivot-point, as at W, (see Fig. 3.) for engagement by the tappet-wheel teeth N, whereby oscillating 95 motion is imparted to the arm U and an alarm effected.

It is intended that the tappet-wheel M shall be held against rotation in one direction—in other words, that the friction or operating wheel K shall be locked therewith through means of the pin P and ratchet-teeth O when the wheel K is rotated in direction indicated by the arrow in Figs. 1 and 2, and that during reverse rotation of the wheel K the pin P shall slide from tooth to tooth O on the wheel M through yielding action of the spring R. The extended end W of the oscillating lever U is yieldingly held into engagement with the tappet-wheel teeth N by means of a spring W', having one end secured thereto and its other end secured to the arm D.

The construction of my improved alarm will be understood from the above description. In the use thereof on a window the plate A is secured to the upper right-hand cover of the lower sash, with the longer or curved end F of the arm D extending thereabove and backwardly, holding the operating-wheel K against the adjacent side rail of the upper sash of the window.

10 The arm D being held by tension of the spring G', forcing the wheel K against the upper sash, it is apparent that should the lower sash be raised or the upper sash lowered the wheel K, through its frictional engagement 15 with the upper sash, will be imparted rotation (indicated by the arrows in Figs. 1 and 2) and through its locking connection with the tappet-wheel effect likewise rotation of the latter wheel. During rotation of the 20 wheel M, as just described, its tappets N will impart oscillating action in the arm U, causing its headed end T to strike and intermittently sound the bell. Movement of the longer end F of the arm D toward the upper 25 window-sash may be adjusted by means of the screw H, and when it is desired to raise or lower the sashes without sounding the bell the wheel K is adjusted backwardly from its operating position by simple pressure on the 30 shorter or finger end E of the arm D. The screw H has further usefulness in serving as a stop to prevent movement of the arm D, carrying the operating-wheel out of working position when the upper sash is completely 35 lowered.

Having thus described my invention, what I claim as new, and desire to secure by Letters Patent, is—

1. The combination in an alarm, of an arm 40 pivoted between its ends to a suitable support, leaving one end extended, providing a finger end, whereby to operate the lever, an operating-wheel at the other end of the arm, a tappet-wheel on said arm driven through 45 ratchet means upon rotation in one direction

of the operating-wheel, a suitably-supported bell, an oscillating arm having one end in contact with the tappet-wheel, and its other end adapted to strike the bell, a spring holding the oscillating arm under tension, and a 50 spring under the finger end of the pivoted arm holding same yieldingly elevated, substantially as described.

2. The combination in an alarm, of a suitable base, an arm pivoted between its ends, 55 to the base, an operating-wheel at one end of said arm, a tappet-wheel at the same end of said arm, ratchet-teeth on the tappet-wheel, a yielding dog on the operating-wheel, the dog being arranged in engagement with said 60 ratchet-teeth, a suitably-supported bell, an oscillating arm having pivotal support on the pivoted arm, the oscillating arm having one end in engagement with the tappet-wheel and its other end adapted to strike the bell, a 65 spring holding the pivoted arm under tension, a spring holding the oscillating arm under tension, and means limiting movement of the pivoted arm, substantially as described.

3. The combination in an alarm, of a suitable base, an arm pivoted between its ends to the base, an operating-wheel at one end of said arm, a tappet-wheel at the same end of the arm, ratchet-teeth on the tappet-wheel, a pin on the operating-wheel held yieldingly in 75 engagement with said ratchet-teeth, a bell having support on the pivoted arm, an oscillating arm having support on the pivoted arm, springs holding the pivoted and oscillating arms under tension, the oscillating 80 arm having one end in engagement with the tappet-wheel, and its other end adapted to strike the bell, and a screw on the pivoted arm adapted for adjustment limiting movement of the pivoted arm, substantially as described. 85

FRANCIS MARION HOBBS.
